Assistant Examiner — Darryl J Dardenne

(57) **CLAIM**

The ornamental design for a shot glass, as shown and described.

DESCRIPTION

FIG. 1 is a top perspective view of a shot glass showing my new design;

FIG. 2 is a front elevational view thereof, the rear elevational view being a mirror image thereof;

FIG. 3 is a top plan view thereof;

FIG. 4 is a bottom view thereof;

FIG. 5 is a right-side elevational view thereof, the left-side elevational view being a mirror image thereof;

FIG. 6 is an exploded top perspective view thereof;

FIG. 7 is an exploded bottom perspective view thereof; and, FIG. 8 is an exploded front view thereof.

The broken lines shown FIGS. 4, 6, and 7 are included for the purpose of showing environmental structure and form no part of the claimed design.

1 Claim, 8 Drawing Sheets(56)
